W. B. GEORGE,
CALIPERS AND SIMILAR TOOL,
APPLICATION FILED FEB. 16, 1915.

1,171,040.

Patented Feb. 8, 1916.

UNITED STATES PATENT OFFICE.

WILLIAM B. GEORGE, OF CHICAGO, ILLINOIS.

CALIPERS AND SIMILAR TOOL.

1,171,040.

Specification of Letters Patent. Patented Feb. 8, 1916.

Application filed February 16, 1915. Serial No. 8,441.

To all whom it may concern:

Be it known that I, WILLIAM B. GEORGE, a citizen of the United States, and a resident of the city of Chicago, in the county 5 of Cook and State of Illinois, have invented certain new and useful Improvements in Calipers and Similar Tools; and I do hereby declare that the following description of my said invention, taken in connection with the 10 accompanying sheet of drawings, forms a full, clear, and exact specification, which will enable others skilled in the art to which it appertains to make and use the same.

My invention relates to improvements in 15 calipers and similar tools and more particularly to that class known as registering calipers.

The principal objects of my invention are to so construct a tool of this character that 20 it may be easily and conveniently manipulated, to so locate and arrange the graduated scale that it may be quickly and accurately read, to make provision for adjustment to take up wear, and to provide both a vernier 25 and regular scale on the same instrument.

To attain these and other objects my invention consists in the novel and peculiar arrangement and combination of parts as hereinafter first set forth and described and 30 particularly pointed out in the claims.

In the sheet of drawing which serves to illustrate my said invention more fully, Figure 1 represents a side elevation of my improved tool. Fig. 2 is an edge elevation of 35 the tool looking in the direction of the arrow X in Fig. 1. Fig. 3 is a fragmentary side elevation of my improved caliper constructed with straight inside legs. Fig. 4 is a fragmentary side elevation of my improved 40 caliper having correspondingly curved opposed outside legs. Fig. 5 is an end view of my improved caliper. Fig. 6 is an enlarged fragmentary longitudinal section on line 45 6-6 of Fig. 1, looking in the direction of the arrows. Fig. 7 is a fragmentary section 50 on line 7-7 of Fig. 1 to illustrate the joint construction. Fig. 8 is a fragmentary edge view to illustrate the means for adjustment of the graduated segment. Fig. 9 is a fragmentary side view to show the vernier scale 55 on the side of the segments opposite the regular scale shown in Fig. 1.

Like parts are indicated by corresponding

characters or symbols of reference in all the figures of the drawings.

My improved tool comprises two members each preferably of angular form which in Fig. 1 of the drawings I respectively designate by the letters A and B. These members when properly assembled cross each other 55 at a medial point and are pivoted to each other by a pivot 1 provided with opposed circular flanges or heads 2 between which the members are pivotally mounted. As shown in Figs. 1, 2, and 7, the members are 60 recessed or cut out to provide opposed concentric walls or shoulders 3 and 4.

The member A, as shown in Fig. 1, consists preferably of a curved caliper leg 5, projecting on one side of its pivot point, a 65 hand grasping part 6, projecting on the opposite side of its pivot point, and a segmental arm 7, extending laterally from the outer extremity of the hand grasping part. By referring to Fig. 8, it will be noted that 70 the outer end of the hand grasping part is slotted as shown at 8 to provide a bifurcated extremity and the upper fork of said end is also provided with two holes 16. The purpose of this construction is to provide means 75 of adjustment for the segmental arm 7, the inner end of which is fitted in the slot 8, and adjustably fastened there by screws 10 which fit through the transverse slots 9 and screw into suitable openings in the segmental arm.

The other member B likewise consists of a caliper leg 11 which is preferably of angular form and extends on one side of its pivot point, a hand grasping part 12, extending 80 on the other side of its pivot point, and a segmental arm 13, which is preferably made considerably shorter than the segmental arm 7, and is suitably fastened at its inner end by a screw 14 to the outer extremity of the 85 hand grasping part 12 and in a position exterior to and concentric with the segmental arm 7, as shown in Fig. 1.

It is now to be pointed out that the segmental arms 7 and 13 are disposed in the 90 same plane, this construction being accomplished by offsetting the bifurcation at the end of the hand grasping part 6 of the member A, which receives the end of the segmental arm 7, and by making the end of the 95 hand grasping element of the member B

thinner than the main portion thereof, as seen in Fig. 6, whereby the segmental arm 13 may be fastened upon the inner face thereof, thereby disposing both of said arms 5 in the same plane, in an evident manner.

For simplicity in construction and convenience in manipulation I prefer to provide a regular scale on one side of each of the segmental registering arms and a vernier 10 scale on the opposite side thereof. It should, however, be understood that I may in some instances omit one or the other of these scales from my invention or employ other suitable means of registering.

15 In Fig. 1, I have shown a series of graduations 15, on the inner segmental arm 7, which represents the regular scale. In Fig. 9, the opposite sides or faces of the inner and outer concentric segmental arms 7 and 20 13 are illustrated, with a series of vernier scale graduations 17 on the arm 7, graded at about forty to the inch, and a registering series of vernier graduations 18 graded at about twenty-five in 24/40 inch on the 25 arm 13.

The caliper legs of this improved tool may be made in any desired shape suitable for either inside or outside work, for instance, in Fig. 1, the leg 5 is curved while the leg 30 11 is angular, in Fig. 3 both the legs which are indicated by a similar numeral 19 are straight and of corresponding form suitable for inside work, and in Fig. 4 both the legs, indicated by the same numeral 20, are 35 curved correspondingly and opposed to each other, being suitable for outside work.

The members A and B are maintained in adjusted position by a stud 21 passing through a boss 22 on the member 12, which 40 stud is possessed of a slot embracing the inner edge of the segment 7, and, upon its outer or opposite end, is possessed of a suitable screw thread, engaging a knurled nut 23, or like media, whereby the said segment 45 7 and the member 12 may be fixedly clamped together, as clearly seen in Fig. 6.

It will be noted that the hand grasping part 12 of the member B is provided with an opening 24 of sufficient size to permit the 50 insertion therein of the thumb of the operator's hand and that the opposite hand grasping part 6 of the member A also is constructed with an opening 25 which is longer than the opening 24 to permit the remaining fingers of the hand to be entered therein. The object of this construction is to provide a firm and secure grasp for the hand of the operator. It should, however, be understood that these openings may be omitted 55 if desired.

While I have illustrated and described a preferred form of construction for carrying my invention into effect, this is capable of a wide range of variation and modification 60 without departing from the spirit of my in-

vention, I therefore do not wish to be limited to the details of construction herein set forth but desire to avail myself of such variations and modifications as fairly fall within the scope of the appended claims.

Having thus fully disclosed my invention I claim as new and desire to secure to myself by Letters Patent of the United States:

1. An article of the class described including a pair of members pivoted together intermediate their length and possessed of opposite ends, measuring legs comprising one of the ends of said members, the opposite end of one of said members being bifurcated, an arcuate registering blade having one end fixed in said bifurcation, there being slotted means in said blade permitting lateral adjustment thereof, and a coacting blade, fixed to the opposite end of the other of said members. 75

2. An article of the class described including a pair of members pivoted together intermediate their length and possessed of opposite ends, measuring legs comprising one of the ends of said members, the opposite end of one of said members being bifurcated, an arcuate registering blade having one end fixed in said bifurcation, and a coacting arcuate blade, the inner periphery of which contacts the outer periphery of 95 said first named blade and fixed to the opposite end of the other of said members.

3. An article of the class described including a pair of members pivoted together intermediate their length and possessed of opposite ends, measuring legs comprising one of the ends of said members, the opposite end of one of said members having an arcuate blade extending laterally beyond said member, and the other of said members being possessed of a coacting arcuate blade, the inner periphery of which contacts with the outer periphery of said first named blade, both of said blades being located in the same plane. 100

4. A tool of the class described comprising two members pivotally connected at an intermediate point, and having measuring legs on one side of said pivoting point, hand grasping parts on the opposite side of said pivoting point, one of said hand grasping parts having a slotted extremity, a segmental registering arm adjustably secured in said slotted extremity, another segmental registering arm secured to the other hand grasping part and concentric to the adjustable segmental arm. 110

5. An article of the class described including a pair of members pivoted together intermediate their length and possessed of opposite ends, measuring legs comprising one of the ends of said members, the opposite end of one of said members having an arcuate blade extending laterally beyond said members, and the other of said members being possessed of a coacting arcuate blade, 125

the inner periphery of which contacts with the outer periphery of said first named blade, but is shorter than said first named blade, both of said blades being located in 5 the same plane.

6. An article of the class described including a pair of members pivoted together intermediate their length and possessed of opposite ends, measuring legs comprising 10 one of the ends of said members, the opposite end of one of said members having an arcuate registering blade, and means near

the opposite end of the other of said members engaging the inner edge of said blade and rendering said members immovable with 15 respect to each other.

In testimony whereof I have hereunto set my hand in the presence of two subscribing witnesses.

WILLIAM B. GEORGE.
